UNITED STATES PATENT OFFICE.

ALEXIS IWANOV POLIANSKY, OF ST. PETERSBURG, RUSSIA.

FLOAT.

No. 806,490.

Specification of Letters Patent.

Patented Dec. 5, 1905.

Application filed February 14, 1905. Serial No. 245,681.

To all whom it may concern:

Be it known that I, ALEXIS IWANOV POLIANSKY, a subject of the Emperor of Russia, residing a 158 Newsky Prospekt, St. Petersburg, in the Empire of Russia, have invented a new and useful Improvement in Floats, of which the following is a specification.

My invention relates to inflatable floats, and has for its object to provide the same above and below along the longitudinal and transverse edges with loops and turn-buttons or like fastening devices for enabling any desired number of such floats to be easily and rapidly connected with each other to constitute rafts, floating bridges, or the like.

In the accompanying drawings I have represented a constructional form of my said invention, Figure 1 showing a collapsed float, and Fig. 2 showing an inflated float ready for use.

This float consists of a prismatic rubber balloon or receptacle, Fig. 2, inclosed in a strong water-tight linen covering and provided with a valve *a*, through which air may be blown in. When the balloon, the construction of which presents no novel features, is not inflated, its ends may be bent inward and its sides outward or the sides inward and the ends outward, so that the upper wall will lie directly upon the lower wall. In this state the balloon occupies as little space as possible and is adapted for transport, Fig. 1. Along the upper and lower longitudinal and transverse edges of this float I fix several loops *b* and turn-buttons *c* or like fastening devices by means of bands *d*, sewed on or otherwise. Any number of floats furnished in this manner with loops and turn-buttons or the like may thus be easily and instantaneously con-

nected with each other, the floats adjoining either at the sides or at the ends, or both at the sides and ends. By this means bridges, rafts, or other floating appliances may be formed of one or more rows of inflated floats, such bridges having an enormous carrying power. For instance, a float of twenty-eight inches in length and twelve inches in depth and width which one man can inflate without any difficulty has a carrying power of about two hundred and two hundred and fifty pounds.

Having regard to the convenient transport and easy connection of the floats with each other for the various applications, these floats are particularly suitable for military purposes in countries which are destitute of wood or in the case of insufficient communications.

What I claim as my invention, and desire to secure by Letters Patent, is—

1. In a device of the character described, the combination, with two inflatable balloons, of coöoperating loops and turn-buttons fastened along the upper and lower longitudinal and transverse edges of the same, substantially as and for the purpose herein set forth.
2. In a device of the character described, the combination with two balloons, of loops *b* and turn-buttons *c* attached to said balloons in such positions as to coöperate with each other, and bands for securing said loops and buttons in place.

In testimony whereof I have signed my name to this specification in the presence of two subscribing witnesses.

ALEXIS IWANOV POLIANSKY.
